(57) **CLAIM**

The ornamental design for a motorcycle wheel front face, as
shown and described.

DESCRIPTION

FIG. 1 is a front perspective view of my new motorcycle
wheel, according to the present invention; and,
FIG. 2 is an enlarged front elevational view thereof.

The broken lines shown in FIGS. 1 and 2 of the drawings are
for illustrative purposes only, and the subject matter depicted
thereby constitutes no part of the claimed design.

1 Claim, 1 Drawing Sheet

FIG. 1.

FIG. 2.
